(57) **CLAIM**

The ornamental design for an electrical machine rotor lamination segment, as shown and described.

DESCRIPTION

FIG. 1 is a perspective view of a first embodiment of an electrical machine rotor lamination segment showing my new design;

FIG. 2 is a top plan view thereof;

FIG. 3 is a bottom plan view thereof;

FIG. 4 is a left side view thereof;

FIG. 5 is a right side view thereof;

FIG. 6 is a rear side view thereof;

FIG. 7 is a front side view thereof;

FIG. 8 is a perspective view of a second embodiment of an electrical machine rotor lamination segment showing my new design;

FIG. 9 is a top plan view thereof;

FIG. 10 is a bottom plan view thereof;

FIG. 11 is a left side view thereof;

FIG. 12 is a right side view thereof;

FIG. 13 is a rear side view thereof; and,

FIG. 14 is a front side view thereof.
